PROCESS FOR CONVERTING PETROLEUM HYDROCARBONS

Albert G. Davis, Elizabeth, N. J., assignor, by
mesne assignments, to Gasoline Products Com-
pany, Inc., Wilmington, Del., a corporation of
Delaware

Application January 18, 1926. Serial No. 81,915

5 Claims. (Cl. 196—51)

This invention relates to improvements in a process for converting hydrocarbons, and refers more particularly to a cracking process in which the oil, after being converted or cracked, is passed to a separate stage for distillation, and in this stage of distillation or evaporation is introduced a relatively heavy hydrocarbon medium, the character of this medium being such that substantially none is volatilized or vaporized at the temperatures existing in the vaporizing stage. Such a blending product would be similar in its characteristics to the unvaporized or residual material withdrawn from the vaporizing stage, and this product, it has been found, is admirably adapted to be utilized as a blending product with the cracked hydrocarbons and is used in a manner hereinafter described in more detail.

The single feature is a diagrammatic side elevational view of apparatus for carrying out a cracking process in which this blending of relatively heavy material is employed by the introduction of the blending oil to the transfer line between the reaction stage and the vaporizing stage, although it is understood that the blending may be effected by introducing the blending oil directly to the evaporating stage.

In the figure, at 1 is shown a furnace consisting of a combustion chamber 2 and a coil compartment 3, in which are mounted the pipe coils 4. The furnace is preferably heated by means of gas burners diagrammatically shown at 5; gas passing from the combustion zone over the tubes and out through the flue 6 which is connected to a chimney or stack 7. At 8 is shown an enlarged heavily insulated forged steel reaction chamber preferably fabricated from a single ingot and forged into an elongated tube having bottle-neck ends. Removable end plates are attached to the flanges and adapted to be removed for the purpose of cleaning. The chamber is mounted upon suitable piers shown at 9. The discharge from the reaction chamber is directly connected by means of a transfer line 10 to an evaporating tower 11 which, in turn, is connected by means of a vapor pipe 12 to a diphlegmating tower—preferably of bubble type construction—shown at 13. The top of the bubble tower has communication through a vapor line 14 with a coil 15 in the condenser box 16, the discharge end of which connects by means of a pipe 17 to the gas separator 18—the latter being equipped with a gas outlet 19 and a liquid draw off line 20, the lines 19 and 20 being controlled by valves 21 and 22, respectively. The liquid level in the evaporator 11 is controlled by means of a liquid level regulating

device 23 manipulating the valve 24 positioned in the draw off line 25. This draw off line terminates in a coil 26 positioned in the cooling box 27. This discharge from the cooling coil 26 is directed to the accumulating tank 28 which is equipped with two draw off lines 29 and 30, the former communicating with a storage receptacle not shown and the latter with the suction side of the pump 31. Each of the lines is equipped with a valve designated as 32 and 33, respectively. 65

The liquid level in the bubble tower or diphlegmator is controlled by means of a liquid level regulating device 34 manipulating the valve 35 in the draw off line 36 which has communication with a return line 37 connected to the suction side of the pump 38 and a line 39 communicating with a storage receptacle not shown. The lines 37 and 39 are controlled by valves 40 and 41, respectively.

Steam lines 42 and 43 connect into the bottom 75 of the evaporator 11 and the bubble tower 13 whereby steam may be introduced to the separate stages in controlled quantities as desired.

Referring now to the operation of the process, the major stages of which follows the practice 80 of the cross process, is as follows:

Charging stock is introduced from any convenient source through the line 44 and is charged by means of a pump 45 through a preheating coil 46 positioned in the top of the evaporating tower 85 11. The preheated oil is then directed through the line 47 to the coils 4 positioned in the furnace 1. On its discharge from the heating coils 4, the oil has reached a cracking temperature but conditions and velocity of the oil through the 90 coils is so regulated that carbon deposition is substantially eliminated from the coils. From the heating coils, the oil is directed to the reaction chamber where it is collected in a considerable body and remains for a sufficient period 95 of time to undergo adequate digestion, that is, to complete the cracking reaction initiated in the heating coil. The reaction chamber 8 is heavily insulated to prevent the loss of heat by radiation. The chamber is equipped with pressure recording 100 gauge 48 to facilitate the pressure control. Temperatures and pressures are regulated to effect the conversion of the oil while the same is maintained substantially in the liquid phase or without substantial vaporization. 105

The synthetic crude or cracked products are discharged from the reaction chamber 8 through the transfer line 10 in which is interposed a pressure reduction valve 49. There is also connected into this transfer line posterior to the 110

valve 49 a line connection 50 which communicates with the discharge from the pump 31. The cracked or synthetic products, in a highly heated condition and at high pressures, pass through the transfer line into the evaporator where a substantially lower pressure is maintained than that existing in the reaction chamber. With this reduction of pressure, and due to the contained heat of the oil, the volatile or lighter products 10 evaporate off, passing overhead through the line 12 to a bubble tower or dephlegmator 13 where they are subjected to a refluxing action after which the still volatile material passes off from the top of the tower through the line 14 to the condenser 15 and finally into the gas separator 18.

The reflux material knocked back in the bubble tower is drawn off through the line 36 and recirculates back to the heating coil through the line 37 and pump 38 or it may be diverted from the system through the line 39. The bottoms withdrawn from the evaporator which comprises a relatively heavy liquid hydrocarbon unvaporized at the temperature conditions existing in the evaporator, are drawn off through the line 25 controlled by a valve 24 and, after passing through a cooling coil 26, are collected in an accumulating or settling tank 28 from which tank they may be diverted to storage or returned by 30 means of the pump 31 and charged into the vaporizing stage through the pipe 50 which communicates, as previously stated, with the transfer line 10. It is this recycling or the utilization of a relatively heavy liquid hydrocarbon which 35 will not readily vaporize at the temperature conditions existing in the evaporator when used in a process of the type described, that forms the novelty of the invention as the practice described in connection with the main apparatus itself is an 40 operation well known in the art. It is recognized that it is common practice to introduce a cool hydrocarbon to the evaporating stage to retard, to a certain extent, the evaporation taking place in the vaporizing stage, but it is thought novel 45 to select a particular hydrocarbon having the characteristics hereinafter described in more detail for an operation of the type described and particularly the residual material withdrawn from the evaporating stage for circulation back 50 into the system as the blending medium for the synthetic or cracked products discharged from the reaction stage into the evaporator. It is thought to be new, also, to utilize a medium such as a residual product drawn off from the evaporator as a blending oil with the synthetic crude 55 or cracked products discharged from the reaction stage in a system wherein the synthetic products are passed, without cooling, from the reaction stage to an evaporating stage. Where the synthetic crude is discharged in a highly heated 60 condition from the reaction stage, it is normal practice in the production of gasoline distillates directly from the system to partially cool the oil prior to vaporizing it, as otherwise excessive evaporation takes place, resulting in the distillation of certain of the objectionable high-boiling point products which tend to overload the refluxing and fractionating system beyond its capacity and, furthermore, producing an objectionable residual bottom in the evaporator such 65 as a non-fluid residuum or coke.

By utilizing the liquid bottom withdrawn from the evaporator, substantially none of such a cooling medium recycled through the pump 31 as described, is evaporated overhead from the evap-

orating stage as it has already been subjected to the temperature conditions existing in the evaporator. This is an important operating point as it cuts to a minimum the vapor to be carried over to the refluxing or fractionating system. 80 In other words, no vapor is carried to the refluxing apparatus except the normal fractions of the synthetic or cracked products lighter than the residuum.

Furthermore, the practice as described promotes the production of a lower percentage of residual products as the operator can control the gravity of the unvaporized products taken off from the evaporator at a lower point by this method without the danger of advancing into the zone of operation wherein there is objectionable coke formation. This accuracy of control is important as it automatically increases the percentage of recharging stock produced as a somewhat deeper distillation cut can be made into 95 the cracked product than where cooling is relied upon to prevent the passage overhead of too great an amount of these higher boiling point fractions. This increase in the percentage of recharging stock in turn shows a greater ultimate 100 yield in the gasoline, as this yield is to a great extent dependent upon the percent of recycled stock.

The system has the further advantages that less fluctuation occurs in the temperature control of the evaporator than when using a charging stock as a blending medium. It has been found, under certain conditions, advantageous to introduce steam into the bottom of the evaporator through the line 42 by means of a perforated pipe in the bottom of the evaporating tower by means of which a better control is obtained on the flash point and the initial boiling point of the residual or unvaporized bottoms withdrawn from the evaporator. The utilization of 115 these residual products, as previously described, permits the passing of the synthetic crude directly to the evaporator without first passing the cracked products or synthetic crude through a cooling stage. It has been found of considerable 120 advantage in operating a system of this type to introduce steam into the bottom of the bubble tower or dephlegmating column 13 to facilitate the evaporation of the reflux material. This steam is introduced by means of the line 43 in 125 quantities regulated according to the operating conditions existing in the tower.

This type of blending oil has the effect of preventing carbonization or carbon collection in the transfer line and assures the discontinuance of 130 cracking at the point of pressure reduction or prior to the introduction of the synthetic crude to the evaporator. Furthermore, it has the effect of producing a more uniform residual material ultimately withdrawn from the evaporating stage. The accumulating tank serves not only to maintain a constant and adequate supply of the medium for circulation through the pump 31, but permits the residual material to collect in a stagnant pool wherein the free carbon particles will have ample opportunity to settle out, thereby relieving the system of accumulations in the active operating stages.

I claim as my invention:

1. A process of converting petroleum hydro- 145 carbons, comprising the steps of subjecting the oil to cracking conditions of temperature and pressure in a heating stage, passing the oil to a digesting stage wherein it is maintained at a cracking temperature while under pressure, 150

- passing the cracked products to a zone of reduced pressure wherein the lighter fractions are distilled off, introducing into the zone of reduced pressure a hydrocarbon medium substantially none of which will volatilize in the reduced pressure zone. 5
2. A process of converting petroleum hydrocarbons, comprising the steps of subjecting the oil to cracking conditions of temperature and pressure in a heating stage, passing the oil to a digesting stage wherein it is maintained at a cracking temperature while under pressure, passing the cracked products without cooling to a zone of reduced pressure wherein the lighter fractions are distilled off, introducing into the zone of reduced pressure a hydrocarbon medium substantially none of which will volatilize in the reduced pressure zone. 10
3. A process of converting hydrocarbon oil comprising subjecting the oil to cracking conditions of temperature and pressure in a heating stage, passing the oil to a digesting stage wherein it is maintained at a cracking temperature while under pressure, passing the products of 20 conversion to an evaporating stage maintained at a pressure materially lower than that in the digesting stage, distilling off the lighter fractions of the products of conversion, withdrawing the unvaporized products from the evaporating stage, cooling the unvaporized products and re-
- cycling them to the evaporating stage to check the cracking reaction. 15
4. A process of converting petroleum hydrocarbons, comprising the steps of subjecting the oil to cracking conditions of temperature and pressure in a heating stage, passing the oil to a digesting stage wherein it is maintained at a cracking temperature while under pressure, passing the cracked products to a zone of reduced pressure wherein the lighter fractions are distilled off, introducing into the zone of reduced pressure a hydrocarbon medium substantially none of which will volatilize in the reduced pressure zone and introducing steam into the cracked products in the reduced pressure zone. 25
5. A process of converting petroleum hydrocarbons, comprising the steps of subjecting the oil to cracking conditions of temperature and pressure in a heating stage, passing the oil to a digesting stage wherein it is maintained at a cracking temperature while under pressure, passing the cracked products into an enlarged evaporating stage maintained under a relatively low pressure wherein the lighter fractions thereof are distilled off, fractionating said lighter fractions 30 to condense and separate higher boiling constituents therefrom, withdrawing the unvaporized products from the evaporating stage and returning the unvaporized products to the evaporating stage to check the reaction. 90
